AEROPLANE PROJECTILE

Original Filed Jan. 19, 1918. 2 Sheets-Sheet 1

Ma.1.

A technical drawing of a door assembly. It shows a rectangular door frame with a vertical door panel. On the left side of the door panel, there is a handle and a lock mechanism. The handle is a vertical rod with a circular grip at the top. Below the handle, there is a rectangular lock body with a keyhole. The door panel is labeled with the number '15' at the top and '18' at the bottom. The entire assembly is labeled with the number '2' at the bottom left.

UNITED STATES PATENT OFFICE.

ALBERT ENNIS HENDERSON, OF TORONTO, ONTARIO, CANADA.

AEROPLANE PROJECTILE.

Application filed January 19, 1918, Serial No. 212,618. Renewed March 5, 1927.

The object of the invention is to provide in connection with an aeroplane, designed as an offensive, military, or war plane, a means for accurately projecting, discharging, or releasing a bomb, torpedo, or other missile, with reference to a specific objective, and for facilitating the directing or aiming of the projecting means with regard to said objective, illuminating or spotting devices being available for night use, or when the atmosphere is murky, or otherwise lacks clearness.

Further objects and advantages will appear in the course of the following description, it being understood that changes in form, proportion, and details of arrangement may be resorted to within the scope of the appended claims without departing from the spirit of the invention.

20 In the drawings:

Figure 1 is a side view of an aeroplane provided with an equipment embodying the invention in a preferred form.

25 Figure 2 is a plan view of the same.

Figure 3 is a front view.

Figure 4 is a detail view in section of the projectile directing and discharging means.

Figure 5 is a view of a sighting device for cooperation with the projecting means.

30 Figure 6 is a view of a binocular sighting device.

Figure 7 is a view of a convenient form of binocular support.

In the illustrated embodiment of the invention, the supporting vehicle or vessel from which the offensive missile is to be discharged, is represented by an aeroplane of which the body portion consists of a fuselage 10 which, in this instance, is of single or unitary form, at the forward end of which is arranged the fixed or stationary plane structure embodying upper and lower planes 11 and 12, and in advance of which is arranged the ascending plane 13, which is adjustable or movable on a horizontal axis, and at the rear end of the fuselage are arranged the auxiliary adjustable ascending planes 14 and rudders 15, any suitable means for securing the desired movement or relative adjustment thereof being employed, but not being specifically illustrated herein for the reason that such devices are of common knowledge in this art. Also associated with the main forward sustaining planes are the ailerons 16 which, as in the ordinary practice, are

adapted for use as lateral balancing means and for securing the lateral tipping or tilting of the structure in curved or spiral flights. In this instance two propellers 17 are illustrated, but it is obvious that this feature may be modified to suit the conditions under which the device is designed to be employed.

Disposed preferably above the center of resistance of the structure, or above and approximately parallel with the axis of the fuselage is a series of auxiliary dirigible sustaining planes 18 preferably arranged in two parallel groups one of which is disposed on either side of the vertical plane of the axis of the fuselage and which are adapted for simultaneous deflection from a flat or horizontal plane to afford greater or less sustaining force, or to be arranged at a greater or less incidence so as to modify to a greater or less extent the vertical or lifting component of the dynamic resistance. Obviously, however, as may be determined by experiment, or to meet varying conditions of use, the extent of deflection, or movement from an assumed neutral position, may be varied as to the respective planes in the series, as for example, the foremost, or the foremost and rearmost planes of the series may be movable simultaneously with the intermediate planes of the series but to a greater extent and yet be adapted by a corresponding ratio in return movement, to resume the neutral position in conformity with that of the said intermediate planes. Also, as above indicated, these auxiliary sustaining planes are preferably arranged in parallel groups at either side of the vertical plane of the axis of the fuselage, so as to afford an additional stabilizing means, and when this arrangement is adopted the intervening space may be utilized to provide for positioning in the vertical plane of the axis of the fuselage, and also above the horizontal plane thereof of axially vertical drifting planes 19, preferably coupled with actuating means whereby a simultaneous and proportionate adjustment thereof may be secured, either to cause deflection in one direction or the other from the vertical plane of the axis of the fuselage, or accurate alinement with said plane. The series of drifting planes as well as the series of auxiliary sustaining planes preferably extend approximately throughout the length of the fuselage, at

least in rear of the main sustaining planes, and may as shown be extended over the main sustaining plane structure, with one or more of the elements thereof in advance of the 5 same to more effectively reinforce the action of the main sustaining plane when abrupt changes in condition occur or prompt alteration in direction of movement is required. By means of the drifting planes it is possible 10 to compensate for or neutralize the effect of side winds or drifts of air to adapt the craft to proceed in a direct line toward its objective and thus avoid the disadvantage incident to heading the craft more or less 15 into the wind, as in the ordinary practice, and thus pursuing a more or less circuitous or indirect route. By means of the auxiliary sustaining planes whereby the elevating or lifting component of resistance may be varied, it is possible to reduce the forward speed of the craft so as to time it more or less accurately with that of a moving objective, such, for example, as a watercraft, submarine, or the like.

20 25 Suspended from a point in the fuselage, approximately at the intersection of the longitudinal and transverse axes thereof and adjacent to the center of gravity is a projectile-discharging device 20 which is specifically illustrated in Figure 4, the same being suspended for universal gravitational movement so as to permanently maintain an axially vertical position. To this end the casing 21 is provided with a hollow or tubular neck 22, of which the downwardly convexed head 23 is separated by a concavo-convex floating web 24 from an upwardly concaved seat 25, anti-friction bearing elements, such as balls 26, being interposed between the surfaces of said parts. Extending through the bore of said neck and anti-frictionally supported, as at 27, upon the head 23 is a spindle 28 having means, such as a pulley 29, through which a rapid revoluble movement may be imparted to the spindle, and provided at its lower end with a seat 30 for the reception of the head 31 of a projectile 32, preferably provided with external flanges 33 which progress spirally from one end of the body to the other to impart penetrating power and controlled progressive movement to the projectile when traversing a heavier-than-air medium, such as water. The seat 30 is of cage-like form and is designed to receive the revoluble movement imparted to the spindle and convey it to the projectile preliminary to the release of the latter, of which the head is held seated by means of detents or clutching elements 34, normally held in engaging positions, as by springs 35. When it is desired to discharge or release the projectile it may be accomplished by disturbing the relation of the clutching members with the seated head by the depression of a cap 36 actuated 40 45 50 55 60 65 by a hand lever 37 or its equivalent, said cap containing a cam ring 38 which is anti-frictionally mounted in the cap to avoid impedance of the rotary motion of the clutching member carried by the projectile seat. Said cap is yieldingly sustained by means of springs 39, or their equivalent.

70 75 80 85 90 95 100 105 110 115 120 125 130 In addition to this projectile-discharging or releasing device, the aircraft is preferably provided with sighting apparatus, such as a telescope 40, which may be either of the monocular type, shown in detail in Figure 5, or of the binocular type, shown in Figure 6, at 41. If of the former type, a universal suspending means 42 may be employed, the same consisting of elements 43 and 44, separated by antifriction devices, so that the telescope is free for gravitational movement, and therefore in a cooperative relation with the projectile-discharging means, to facilitate the aiming of the latter so as to properly and accurately approach the objective, whereas if of the binocular type a similar universal and gravitational support of the instrument with the named object in view may be secured by means of a bracket 45 having, for example, a center point 46 disposed between the tubes of the instrument in engagement with a center socket 47 thereon.

130 Also, as a means of aiding the operator in picking up or locating an object at which a projectile or missile is to be discharged, an illuminating means 48 may be employed, the same being shown only in a general or diagrammatic way in the drawing, but being designed for universal or gravitational suspension so as to cooperate accurately with the projectile-discharging and sighting means and may, through any available agency, be of such power as to penetrate the atmosphere, and also a denser medium, if required, even though the former may be obstructed more or less by moisture or smoke. Under any condition, however, the projectile-discharging, sighting and illuminating means should be suspended from the craft under such conditions as to cooperate accurately and be directed without the intervention of the operator along a common path or toward a common objective, so that the operator may be enabled to readily see an object to be attacked and discharge the projectile at the right moment and under conditions most favorable for the purpose in view. Obviously, the accuracy with which this object may be carried out is vastly increased by reason of the control of the craft which is afforded to the operator by such an arrangement of elements as described hereinbefore, and more particularly by reason of the means suggested for permitting the velocity or progress of the craft to be reduced to a minimum while maintaining such an elevation, for example, above the surface of the water in which a submarine may be located, as to enable the projectile to acquire the nec.

essary velocity by gravity before encountering the water, to the end that a sufficiently accurate and rapid progress of the projectile through the water may be attained.

As illustrative, merely, of means for adjusting the auxiliary sustaining and lateral-drift planes, there are shown, in connection with the horizontal axes or shafts 60 of the former (suitable braces 59 being extended 10 to their outer ends) the worms 61 on the longitudinal shaft 62, meshing with worm gears 63 on the shafts 60, while the vertical shafts 64 of the planes 19 carry worm-gears 65 with which mesh worms 66 on the 15 operating shaft 67. Also, guys or braces 59 may be extended to the upper ends of the spindles 64 of the vertical drift planes.

While in the drawings no specific means has been illustrated for imparting revoluble 20 movement to the pulley 29 and hence to the projectile seat, any mechanical contrivance of known capabilities from a hand crank to a high speed motor, utilizing any available motive agency may be employed in this 25 connection, without in any way modifying the purpose or efficiency of the elements herein described which constitute factors of the suspending, directing, revolving and delivering of the projectile under conditions 30 which carry out the indicated objects of this invention.

Having described the invention, what is claimed is:

1. An aeroplane having propelling and 35 guiding means, a projectile discharging means gravitally suspended for universal movement adjacent to the center of gravity of the structure, and means for imparting revoluble or gyratory movement to the projectile.

2. An aeroplane having propelling and guiding means, a projectile discharging means gravitally suspended for universal movement from a point near the axis and the 45 center of gravity of the structure, and means for revolving the discharging means to impart revoluble or gyratory movement to the projectile.

3. The combination with a carrying vessel 50 of a gravitally suspended projectile-seat- ing means comprising a rotatable seat, independent devices for engaging and holding a projectile therein and means for simultaneously releasing said devices, substantially as set forth.

4. The combination with a carrying vessel 55 of a gravitally suspended revoluble projectile seating means, and clamping devices for engaging a seated projectile to communicate the rotative movement of the seat thereto.

5. The combination with a carrying vessel 60 of a gravitally and universally suspended casing, a rotative projectile seat antifriction- ally mounted relatively to said casing, and 65 releasable projectile-holding means for

maintaining a projectile in a seated relation and communicating the rotative movement of the seat thereto.

6. The combination with a carrying vessel 70 of a gravitally and universally suspended casing, a rotative projectile seat having its spindle mounted axially within and carried by the casing, means carried by the seat for engaging and maintaining a projectile in its seated position, and means, including an 75 antifrictionally mounted element for contact with said engaging means, to effect the release of the latter to permit the discharge of the projectile.

7. In a device of the character described 80 an aeroplane capable of being controlled in regard to its vertical and horizontal movements without materially interfering with the horizontal position of the plane, a universally gravitally suspended casing on the aeroplane, an antifrictionally supported rotatable bomb supporting means in the chamber, means for rotating said means, and antifrictional releasing means for the bomb, substantially as set forth.

8. A device of the character described 85 comprising an aeroplane having a gravitally suspended antifrictionally supported chamber, an antifrictionally mounted bomb supporting device within the said chamber having inwardly projecting jaws adapted to engage the upper flanged end of the bomb, means for rotating the said supporting device and the bomb carried thereby, and a 90 releasing device adapted to disengage the jaws without retarding the rotation of the bomb, substantially as set forth.

9. In an aeroplane, a gravitally suspended antifrictionally mounted chamber, a bomb 95 supporting device centrally supported in the said chamber, jaws to engage a flange on the bomb, means for rotating said bomb, antifrictional releasing means, and co-acting sighting devices carried by the plane.

10. In an aeroplane, a gravitally suspended chamber, a bomb supporting device, means for imparting rotation to the said device, and antifrictional releasing means connected with the said chamber, substantially as set forth.

11. An aeroplane bomb having spiral flanges along its downwardly projecting body, a flanged shoulder at its upper end, supporting means adapted to engage the said flange said supporting means being rotatably mounted in a gravitally suspended chamber carried by an aeroplane or other sustaining device, and means for imparting rotation to the said bomb before being released, substantially as set forth.

12. Gravitally suspended antifrictionally mounted bomb supporting means carried by an aeroplane or airship, and means for imparting rotation to a bomb carried thereby, substantially as set forth.

13. A projectile provided with spiral flanges on the body thereof, a radially projecting flange at the upper end, a supporting device having clamping means to engage the 5 radial flange of the projectile said device being antifrictionally journaled in a gravitally suspended chamber antifrictionally mounted at the center of gravity of an aeroplane or other sustaining means (and releasing 10 means carried by the said chamber), substantially as set forth. 14. An aeroplane bomb having spiral flanges, means for supporting and rotating the same, said means being journaled vertically 15 within a gravitally suspended antifrictionally mounted chamber, and an antifrictional releasing device for the bomb carried by an aeroplane or the like, substantially as set forth. 15. A gravitally suspended antifrictionally supported chamber carried by an aeroplane, a bomb supporting device vertically journaled within the said chamber having supporting jaws, an antifriction releasing 20 means for the said jaws, and means for imparting rotation to the said supporting device and bomb before the release of the bomb, substantially as set forth. 16. A bomb for aeroplanes having spiral 25 flanges on its downwardly projecting portion, a shoulder on its upper extremity, a rotatable supporting device engaging said shoulder, said device being antifrictionally mounted in a gravitally suspended universally movable chamber carried by an aeroplane or the like, substantially as set forth. 35 17. For use with an aeroplane projectile having progressive spiral flanges on the body thereof and a radial shoulder at the upper end, supporting means adapted to engage the said shoulder, said means being vertically and antifrictionally journaled within a chamber gravitally suspended from the center of gravity of an aeroplane, means for imparting rotation to the projectile and its supporting means before the projectile is released, and antifrictional releasing means carried by the said chamber, substantially as set forth. 40 45 18. In combination, projectile discharging means suspended for pivoted movement, means for rotating said discharging means and the projectiles therein about a vertical axis, and means to discharge such projectile without interfering with their rotation, substantially as set forth. 50 19. In combination, projectile discharging means suspended for pivoted movement, means for rotating said discharging means and the projectiles therein about a vertical axis, and means to discharge such projectile, substantially as set forth. 60
- In testimony whereof I have hereunto signed my name.

ALBERT ENNIS HENDERSON.
